CLAIM

The ornamental design for a pet bowl, as shown and described.

DESCRIPTION

FIG. 1 is a front, right side, top perspective view of a pet bowl showing my new design;

FIG. 2 is a rear, left side, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a rear, left side, bottom perspective view of the pet bowl in condition for use.

The broken lines in the drawings depict portions of the pet bowl that form no part of the claimed design.

1 Claim, 9 Drawing Sheets
